UNITED STATES PATENT OFFICE.

JOHN O. TRAVELSTEAD, OF PENDLETON, OREGON.

TORPEDO-SHIELD FOR VESSELS.

1,223,536.

Specification of Letters Patent.

Patented Apr. 24, 1917.

Application filed October 14, 1916. Serial No. 125,675.

To all whom it may concern:

Be it known that I, JOHN O. TRAVELSTEAD, a citizen of the United States, residing at Pendleton, in the county of Umatilla 5 and State of Oregon, have invented certain new and useful Improvements in Torpedo-Shields for Vessels, of which the following is a specification.

This invention has reference generally to 10 improvements in guards for vessels, and more particularly relates to a torpedo shield for vessels.

As the primary aim and object, this invention contemplates the provision of novel 15 means for supporting reticulated means laterally of the sides of a vessel and in spaced relation therewith preferably below the water line so as to be invisible, thus serving as an effective means whereby torpedoes will 20 be caught, and in some instances made to explode so as not to seriously injure the vessel carrying the improved guard.

It is an equally important object of the 25 present invention to provide novel means for connecting the shield supporting booms to the sides of the vessel so that the booms may be swung vertically or laterally of the vessel, novel means acting in conjunction with the booms for shifting all of the booms simultaneously 30 toward either end of the vessel, when desired, so that the guard may be subsequently raised to lie in close relation with the sides of the vessel.

The invention also includes the provision 35 of novel means for raising and lowering the booms to consequently hold the shield in various adjusted positions.

More particularly, the present invention embraces the provision of novel foldable 40 shield sections for use at the bow and stern ends of the vessel and for coöoperating with the main shields for effectively guarding the vessel, said sections being arranged so as to be operated by the shifting means for the 45 main shields.

As a further object the invention has to provide novel means for bracing the supports at the bow and stern ends of the vessel for increasing the rigidity of the support 50 with respect to the vessel.

Among the other aims and objects of the invention may be recited the provision of a device of the character mentioned with a

view to compactness, and in which the number of parts are few, the construction simple, 55 the cost of production low, and the efficiency high.

Other improvements and novel details in the construction and arrangement of the various parts of the device, will be brought 60 out more in detail in the description to follow, which for a clear understanding of the invention, should be considered in connection with the accompanying drawings, forming a part hereof, and wherein is disclosed 65 for the purpose of illustration, a convenient and satisfactory embodiment of the invention. It is to be noted, in this connection, that minor changes in the construction and arrangement of the parts may be made without departing from the spirit of the invention, or the principle of operation of the various parts.

The preferred embodiment of the invention is clearly illustrated in the accompanying 75 drawings, in which:

Figure 1, is a fragmentary side elevation of my invention.

Fig. 2, is a top plan thereof.

Fig. 3, is a transverse section showing the 80 invention in a lowered or operative position.

Fig. 4, is a perspective detail, and

Fig. 5, is a fragmentary front elevation of one of the collapsible shields.

Similar characters of reference are employed in all of the above described views, 85 to indicate corresponding parts.

Referring now, more particularly, to the accompanying drawings, I provide a vessel 1 and have connected at uniformly spaced 90 intervals along both sides thereof at points slightly below the water line of the vessel and at points adjacent the bottom of the vessel rows of brackets 2. Each of these brackets includes a base 3 and spaced ears 4. 95 A plurality of booms 5 are now provided and in order to connect the booms so that they may be swung vertically and laterally of the sides of the vessel I employ the plurality of securing elements 6, one end of 100 each of which is bifurcated as indicated by the numeral 7 so that the inner end of each boom may be pivotally connected thereto by means of a suitable fastening device 8, while the opposite end of each element 6 terminates 105 in an eye 9, which is pivotally mounted be-

tween the ears 4 of one of the brackets by means of a suitable pin 10. Rods 11 are employed for connecting the upper booms to the lower booms. In the present instance, one end of each rod terminates in a loop 12 and is arranged between bifurcated ends 13 of the lower boom 5 while the opposite or upper end of each rod has two loops 14 and 15 formed thereon, the former being receivable between the bifurcated end 13 of the upper boom.

With a view toward providing a suitable shield I extend cables 16 through the alined bifurcated ends 13 and loops 14 of each of the upper booms 5 and the rods 11 and have also extended similar cables 17 through the bifurcated ends 13 of the lower boom 5 and the alining loops 12 of the rods 11. As is apparent these cables 16 and 17 serve as a means for holding the rods 11 on the booms so as to permit of pivotal movement of the parts. At this point it will be noted that the lower booms 5 extend downwardly at an angle from the side of the vessel when the upper booms are at right angles thereto being caused by the length of the rods 11 which is greater than the space between the upper and lower brackets 2. Main shields 18 are now provided and may be and preferably are of a reticulated character and include spaced longitudinally and transversely extending pieces which are interwoven to provide fabric structure. Upon reference to Fig. 4 it will be noted that the transversely extending pieces 19 have their outer ends looped as at 20 and engaged about the cables 16 and 17 between which the fabric shields are arranged.

For the purpose of providing suitable means for supporting the guards at the bow and stern ends of the vessel, I have provided my improved supports 21 the inner ends of each of which are bifurcated to provide diverging arms 22 which are secured to the opposite sides of the vessel at the bow and stern ends thereof and at points slightly above the water line by means of suitable fastening devices 23. The supports project fore and aft from the vessel and have their outer ends constructed to form oppositely extending arms 24. Suitable means for bracing the supports in the present instance consists of substantially V-shaped braces 25, each of which is arranged between the arms 24 while the upper brace is anchored as indicated by the numeral 26 to the top of the vessel and the lower brace is secured by means of a suitable fastening device 27 to the bottom of the vessel.

Coöoperating with the main side shields 2 are my improved foldable shields designated each in its entirety by the numeral 28. These shields 28 are arranged in pairs and connected upon opposite sides of the support 21 at the bow and stern ends of the ves-

sel. In the present instance each of these foldable auxiliary shields include four similarly constructed bars 29. The bars 29 have opposite ends connected to each other and at times assume a square shape. The respective ends of the inner bar 29 are looped to pivotally engage eyes 30 and 31 respectively arranged on each support, and on the lower portion of each brace 25, said looped ends also pivotally engaging the inner looped ends of the upper and lower bars 29. The outer bars 29 have their respective ends looped and arranged to register with the outer looped ends of the upper and lower bars so that the looped ends of the mentioned bars may be engaged by the cables 16 and 17. It will now be apparent that inasmuch as the adjacent ends of the bars are pivoted to each other these auxiliary shields may be folded. Each of the bars 29 have a plurality of uniformly spaced eyes 32 formed thereon, and engageable with the eyes are the looped ends 33 of rods 34 which extend longitudinally and transversely of the auxiliary shields.

In order to shift all of the booms 5 laterally to either side so as to consequently arrange the shields 18 in close relation with the sides of the vessel and to also shift the auxiliary shields 28 in a corresponding direction I have extended the respective ends of the cables 16 and 17 and arranged the said cables respectively through pulleys 35 and 36 mounted on the arms 24 and thence extended the cables about drums 37 mounted at the top and at the bow and stern ends of the vessel. Suitable means not shown, may be mounted at these points within the inside of the vessel for operating the cables.

In order to provide suitable means for raising and lowering the shields 18 and for holding them in vertically adjusted positions, I have provided chains 38 and arranged them along the top deck of the vessel adjacent the sides thereof. Auxiliary chain sections 39 extend from the main chains 38 and are trained about pulleys 40 mounted in the eyes 15 on the rods 11 and thence extended toward and connected to the gunwale of the vessel at uniformly spaced intervals as indicated by the numeral 41. Both the main and auxiliary chain sections 38 and 39 operate about rollers 42 mounted at uniformly spaced intervals along the top deck adjacent the sides of the vessel, the main sections 38 being finally passed through an opening 43 at the bow end of the vessel and connected with a suitably operating means (not shown) desirably positioned within the vessel.

For the purpose of raising and lowering the foldable shield to consequently either fold or extend the said shields, I have provided a plurality of chains 44 and connected one end of each to one side of the upper

portion of one of the braces 25, the cable being trained about a pulley 45 connected in an eye 46 formed on the upper end of each of the bars 29 of the foldable shield 3 as indicated in Fig. 5. The chain is now trained about one of the pulley wheels 47 which is mounted in an eye 50 on the side of the upper portion of one of the braces 25 and finally passed through the opening 43 in the deck and arranged for connection with the operating means for the chains 38. With a view toward increasing the rigidity of the supports 21 with respect to upper portion of the braces 25 I have provided 15 rods 51 and arranged one intermediate the ends of each support 21 and upper brace portion 25.

The mode of operation of the present invention may be reviewed as follows:—
20 As illustrated in Figs. 1, 2 and 3, the guard is in a lowered or operative position, the shields 18 being arranged in spaced parallel relation with the sides of the vessel so as to protect the sides of the vessel so 25 as to protect the sides of the vessel, while the auxiliary shields 38 are extended and protect the bow and stern ends of the vessel. Should it be desired to raise the shields the chains 38 are operated so as to consequently draw the shields 18 into a raised position above the water line. The chains 44 are also operated to raise the upper arms 29 of the auxiliary shields 28 to consequently fold the shields and finally the cables 16 and 17 are operated to move the booms 5 30 laterally to consequently arrange the shields 18 in close relation with the sides of the vessel. It is to be understood that various adjustments of the shields 18 and 28 may be obtained by operating various operating 35 chains and cables. Likewise, it is to be appreciated that the device is of such construction that it can be readily attached to and removed from the vessel.

As many changes could be made in the 40 above construction and many apparently widely different embodiments of this invention could be made without departing from the spirit thereof or the scope of the appended claims, it is intended that all matter contained in the above description or 45 shown in the accompanying drawings shall be interpreted as illustrative and not in a limiting sense. It is also to be understood that the language used in the following 50 claims is intended to cover all of the general and specific features of the invention herein described and set forth in the appended claims, which, as a matter of language 55 might be said to fall therebetween.

Having thus described my invention what I claim as new and desire to secure by Letters Patent is:—

1. The combination with a vessel, supporting means extending substantially longitudinally from the bow and stern ends of the ves-

sel, shield members supported by said supporting means and laterally extending from opposite sides thereof for protecting the ends of the vessel, and other shields movably connected to the sides of the vessel and co-extensive therewith and having their ends connected to one of said laterally extending shields, said laterally extending shields being shiftable. 70

2. The combination with a vessel, of brackets connected to the sides of the vessel and arranged in rows at points about the water line and adjacent the bottom of the vessel, supporting booms, connecting elements arranged between the booms and the brackets 75 80 whereby the booms may be swung horizontally and vertically of the sides of the vessel, protecting shields connected to the booms, means for shifting the shields, and means for raising the shields. 85

3. The combination with a vessel, of rows of booms movably connected to the sides of the vessel, vertical rods arranged between the adjacent booms, cables connecting each of the booms and rods, protecting shields arranged between the booms and connected to the cables, means for shifting the shields laterally of the vessel, and means for raising the shields. 90

4. The combination with a vessel, of supports extending longitudinally from the respective ends of the vessel, means for bracing the supports, foldable shields movably connected to the supports and bracing means for protecting the ends of the vessel about the water line, rows of booms movably connected to the sides of the vessel, cables connecting the booms, main shields carried by the cable and co-operating with the foldable shields, the cables being extended to the vessel and operable to shift the shields, means for raising the foldable shields, and means for raising the side shields. 95 100 105

5. The combination with a vessel, of supports extending longitudinally from the respective ends of the vessel, means for bracing the supports on the vessel, means for bracing the bracing means on the supports, foldable shields connected to the supports and the portions of the bracing means beneath the water line, main protecting shields movably connected to the sides of the vessel about the water line and co-operating with the foldable shields, means for raising the main shields, means for raising the foldable 110 115 120 shields, means for shifting all of the shields, and means for guiding the raising and shifting means during operation.

6. The combination with a vessel, supporting means extending substantially longitudinally from the bow and stern ends of the vessel, shield members supported by said supporting means and laterally extending from opposite sides thereof for protecting the ends of the vessel, other shields movably 125 130

connected to the sides of the vessel and co-extensive therewith and having their ends connected to one of said laterally extending shields, said laterally extending shields being shiftable, means for effecting a horizontal folding movement of said laterally extending shields and for maintaining the latter in adjusted positions, and means for ef-

fecting a folding of said side shields to an inoperative position.

In testimony whereof I affix my signature in presence of two witnesses.

JOHN O. TRAVELSTEAD.
